Inventor:—

Samuel H. Terry:—

By *Stanley Stoner* Atty:

UNITED STATES PATENT OFFICE.

SAMUEL H. TERRY, OF ST. LOUIS, MISSOURI, ASSIGNOR OF ONE-HALF TO
SMITH P. GALT, OF SAME PLACE.

DESIGN FOR A METALLIC POST.

SPECIFICATION forming part of Design No. 31,600, dated October 3, 1899.

Application filed July 24, 1899. Serial No. 725,020. Term of patent 7 years.

To all whom it may concern:

Be it known that I, SAMUEL H. TERRY, a citizen of the United States, residing at the city of St. Louis, State of Missouri, have invented and produced a new and original Design for Metallic Posts, of which the following is a specification, reference being had to the accompanying drawings, forming part thereof.

Figure 1 is a side view of the post, and Fig. 2 is a cross-section thereof.

1 and 2 are the two sides, and 3 the connecting portion between them, which form the sides and back of the post. In cross-section the post is practically U-shaped, and it tapers from top to bottom, as shown.

The post is adapted to be used for fences, trolleys, or other purposes.

The essential features are the taper from top to bottom and the cross-section substantially U shape.

Having described my invention, what I claim as new, and desire to secure by Letters Patent, is—

The design for a metallic post, as herein shown and described.

SAMUEL H. TERRY.

In presence of—

R. C. KANN,
STANLEY STONER.
